MULTIPLE CONTROL MECHANISM.

1,425,316.

Specification of Letters Patent. Patented Aug. 8, 1922.

Application filed October 14, 1919. Serial No. 330,672.

(FILED UNDER THE ACT OF MARCH 3, 1883, 22 STAT. L., 625.)

To all whom it may concern:

Be it known that I, LAWRENCE R. BUCKENDALE, captain, Ord. Dept., U. S. A., a citizen of the United States, and a resident 5 of Detroit, Michigan, have invented an Improvement in Multiple Control Mechanism, of which the following is a specification.

The invention described herein may be used by the Government, or any of its officers or employees in prosecution of work for 10 the Government, or by any other person in the United States, without payment of any royalty thereon.

This invention relates to a multiple control mechanism especially applicable to tractors of the self-laying track type where it is 15 essential to obtain separate track manipulation.

One of the fundamental objects of this 20 invention is to perfect a duplex control mechanism involving a series of mechanical assemblies, the different assemblies co-acting to avoid mechanical interference between the active and inactive controlled elements.

Another object of this invention is to design 25 a locking mechanism between the controlling assemblies by which it becomes impossible to actuate any of said assemblies before the clutch has been thrown in or to 30 throw the clutch out until the respective assemblies have been restored to neutral position.

Another object of this invention is to design 35 a control of two units, each unit consisting of a brake and a series of speed assemblies, the two braking assemblies having a common operating member.

Another object of this invention is to provide 40 a control mechanism in which the braking and speed assemblies in each unit are so associated that the braking assembly when operated will apply only in that unit having the inactive speed assembly.

Other objects of this invention are to simplify 45 the prevailing control mechanism for tractors, and to afford ready access to the different assemblies.

With these and other objects in view, my 50 invention consists in certain novel details of construction, combination and arrangement of parts to be more fully hereinafter set forth and claimed.

Referring more particularly to the accom-

panying drawings in which corresponding parts have similar reference characters:— 55

Fig. 1 is a diagrammatic plan view illustrating the complete control layout in association with the rotatable elements of the transmission assembly and clutch mechanism, which is shown in dotted outline; 60

Fig. 2 is a side elevation of the parts as outlined in Fig. 1;

Fig. 3 is a fragmentary perspective view partly in section, of the controlling assemblies, the selector plates for the controlling 65 levers being illustrated in dotted outline;

Fig. 4 is a fragmentary detail view partly in section, the parts in full line being in normal, those in dotted outline being in 70 operative position;

Fig. 5 is a similar view of the high and low speed assemblies, parts in full line showing the normal position, the parts in dotted line illustrating the position assumed by the low speed control assembly when the high 75 speed control assembly is in active position;

Fig. 6 is a fragmentary detail perspective view partly in section of the braking assembly;

Fig. 7 is a similar view of a part of the 80 braking assembly;

Fig. 8 is a similar view of the high speed assembly;

Fig. 9 is a similar view of the low speed 85 assembly;

Fig. 10 is a fragmentary detail perspective view illustrating the locking mechanism as applied to the clutch and braking assemblies, the normal positions of the parts being in full, the operative position in dotted 90 lines; and

Fig. 11 is a top plan view with the selector plate the position of the operating lever being shown in dotted line.

Although as has been previously stated, 95 this invention is capable of more or less general application in connection with power transmission, in the present instance it is described and illustrated in conjunction with a tractor of the track laying type having an 100 especially designed transmission assembly by which the drive is communicated to the tracks through the instrumentality of a plurality of rotatable drums referred to as high, low and braking members 20 and 21, 22 and 105 23, 24 and 25. External contractible band

brakes of ordinary construction are applied to these members and connected with the sectional drag-rods 26 and 27, 28 and 29, 30 and 31, to determine their control. In 5 addition to these details there is of course, the usual clutch and reverse assemblies to be referred to later.

The drag-rods 26 and 27, 28 and 29, 30 and 31 connected to the control assemblies, 10 are suspended in any suitable manner as at 33 and 35 (Figs. 1 and 2).

To further aid in the disclosure of this invention it shall be sub-divided into its component assemblies to-wit; the braking, 15 speed, clutch, reverse and control assemblies to be referred to in the order given. As the high, low and braking assemblies for each track are similar, it necessarily follows that the control units embodying these as- 20 semblies are also identical.

Shaft mounting.—To properly support the various control castings and hangers, there are provided two shafts 36 and 37, mounted parallel and in suitable spaced relation. 25 These shafts usually extend transversely of the tractor, slightly in advance of the operator's position.

Braking control group.—This assembly consists of T shaped hanger 38, having a 30 cored hub on the free end of its shank by which it is suspended from shaft 36, at a point approximately central thereof, (Fig. 6). Centrally connected to the extremities of the hanger cross-head 38, are rocker arms 35 39 and 40, pivotally connected at their lower ends to the brake drag rods 30 and 31.

A brake operating foot lever 41, centrally positioned on shaft 37, is formed with a right-angular extension 42, to which is af- 40 fixed a yoke 43, the free ends of said yoke being affixed to rocker arms 39 and 40 at their fulcrum. Loosely mounted on the shaft 37, on opposite sides of foot lever 41, are sleeves 47 and 48, having external 45 squared portions to which are pivoted speed shifting levers 44 and 45. Toggle arms 49 and 50, extending from the aforesaid sleeves are connected to the upper ends of rocker arms 39 and 40 by the toggle links 51 and 52.

50 On the other hand should the toggle connection between the toggle arms 49 and 50 and the upper ends of rocker arms 39 and 40, be broken as shown in Fig. 4, movement of the foot lever becomes ineffective since 55 the rocker arms on hanger 36, have assumed the position shown in dotted line, Fig. 4, and the swing of said lever is insufficient to take up the slack imparted to the brake sufficiently to apply the brakes.

60 *High speed controlling group.*—This assembly (Fig. 8) comprises hub-like collars which are loosely positioned on the shaft 37, adjacent the squared portions of castings 47 and 48. These collars are formed with 65 selector arms 53 and 54, having laterally

projecting parallel lips 54', at their free ends between which the high and low speed levers 44 and 45 may be positioned.

In addition to the selector arms 53 and 54, the aforesaid collars are provided with 70 toggle arms 55 and 56 and finger-like ex- 75 tensions 61 and 62, the latter being slightly offset with respect to the toggle arms 55 and 56, for a purpose which will appear later. Coacting rods 63 and 64 are fixed at one end 75 to the off-set finger-like extensions 61 and 62, the free ends of these rods being connected to the lower ends of hangers 65 and 66, to which are attached high speed drag- 80 rods 26 and 27. Obviously actuation of the high speed selectors 53 and 54, will through extensions 61 and 62, rods 63 and 64, hangers 65 and 66, operate high speed drag rods 26 and 27.

The low speed control group.—These as- 85 semblies (Fig. 9) embody hub-like collars, mounted on shaft 37, immediately adjacent the collars of the high speed assemblies, and are formed with selector arms 67 and 68, having laterally extending parallel lips 69 90 at their upper ends to receive the high and low speed shifting levers 44 and 45. Said low speed collars are also provided with extensions 70 and 71, to which are affixed one end of connecting rods 73, the other free 95 ends of said rods being connected at the pivotal point of rocker arms 59 and 60, which are centrally pivoted to hangers 76 and 77, suspended from shaft 36, see Fig. 5.

Returning for the moment to toggle arms 100 55 and 56, of the high speed assemblies, it will be seen that the free ends of these arms are connected by toggle links 57 and 58 to the upper extremities of low speed rocking arms 59 and 60, the lower extremities of 105 said arms being attached to the low speed drag-rods 28 and 29. By inter-connecting the high and low speed assemblies in this manner, when the high speed drag-rods 26 and 27 are retracted as outlined in the previous paragraph the toggle connection between toggle arms 55 and 56 and the upper ends of rocker arms 59 and 60 will be disrupted in consequence of which said rocker arms are actuated about their central pivotal 110 connections to the position shown in dotted lines, Fig. 5. This movement of rocker arms 59 and 60, throws considerable slack in the low speed brake bands to complete 115 release of the latter at the time of applying 120 the high speed mechanism.

Clutch control group.—This assembly embodies a suitable hub, mounted on shaft 37, adjacent the collar of the low speed assembly, shown in Fig. 3. It is formed 125 with clutch shifting lever 76, and right angular extending arms 84 and 84', the latter being connected by a clutch rod 85 to the lower end of hanger 85' suspended from shaft 36. The extreme end of said hanger 130

85', is connected to clutch rod 34, which it is understood controls the clutch throw-out mechanism.

Reverse control group.—This assembly 5 comprises a sleeve-like member loosely mounted on shaft 36, and formed with a reverse lever 90, and a finger-like extension 91. Extension 91, is connected by rod 92 to the lower end of hanger 93, suspended 10 from shaft 36, the extreme end of said hanger 93 being pivotally connected to reverse drag-rod 32, controlling the reverse mechanism.

In order to guide and direct the movement 15 of the high and low speed shifting levers 44 and 45 arcuate selector plates 80 are employed having high and low speed ways 78 and 79, formed by a central web 83. This web, which terminates in advance of the low 20 end of selector plate to provide a neutral position for the speed shifting levers is provided with a V shaped notch to receive the similar shaped edge of the shifting lever. This construction forms an interlock to 25 retain the lever in neutral position. Selector plates 80, are also formed with toothed surfaces 83 designed to coact with dogs 95, (see Fig. 4) carried by the levers to retain the latter in their power applying positions. 30 Dogs 95 are disengaged by release means 95' of the usual construction.

To aid in shifting the high and low speed shifting levers 44 and 45, to their respective speed positions retractile springs 81, are 35 connected to said levers and to suitable stops 82. As a precautionary measure against operation of a wrong assembly, if desirable a locking bar 82, may be used, as shown in Figs. 3 and 10. This bar is pivotally 40 connected to an anchoring plate 83', and extends transverse of the several assemblies, overlying arm 84', of the clutch assembly and underlying arms 49 and 50 and 56 of the high speed and braking assemblies. 45 Obviously owing to the position of this bar, it is impossible to actuate any of the speed assemblies until the clutch has been thrown out. Moreover, if any of said assemblies are in operative position, clutch 76, cannot 50 be thrown out until they have been restored to neutral position. It is sometimes desirable to use the locking bar 82 when an inexperienced driver is operating the machine, however, the rest of the inter-locking 55 mechanism will function without this locking bar which is only an additional safeguard.

Operation.—In defining the operation of 60 this invention, to avoid repetition, as the two control units are the same, the components of but one unit shall be considered. Assume reverse lever in forward position and clutch in operative position while all the other parts are in inoperative or neutral position, 65 to apply the low speed mechanism, lever 45

is released from neutral position, shifted laterally into engagement with the low speed selector 68, and then drawn rearwardly to the limit of its movement in selector plate 80. As selector 68, moves rearwardly it causes the lower end of rocker arm 60 to move inwardly describing an arc of a circle having as its center the pivotal connection between toggle links 58, and the upper end of rocker arm 60. The lower 70 end of rocker arm 60 being connected to low speed drag-rod 29, retracts the latter as it moves rearwardly, and consequently applies the low speed mechanism which it controls. 80

To pass now from low to high speed, lever 45 is returned to neutral, shifted laterally therethrough into engagement with high speed selector 54, and then drawn rearwardly to the limit of its throw into selector plate 80. This rearward movement of selector 54 imparts a similar motion to hanger 66, to which it is connected, and thus imparts a rearward pull to high speed drag-rod 27 to effect application of the high speed 90 mechanism which it controls.

When the high speed mechanism is applied, considerable slack is imparted to the low speed drag-rod 29, completely releasing the mechanism which this rod controls. This 95 action is obtained by means of a toggle connection between high speed selector 54 and the upper end of low speed rocker arm 60. When this toggle is broken rocker arm 60, is actuated about its pivotal connection 100 to hanger 77 (as shown in dotted outline, Fig. 5); the lower end of said rocker arm moving outwardly to impart suitable slack to low speed drag-rod 29.

Coming now to the brake control assembly, 105 to apply the brakes, foot pedal lever 41 is depressed, whereupon (the toggle connection between arms 49 and 50 and the upper ends of rocker arms 39, 40 being unbroken), the lower ends of said rocker arms are 110 caused to move inwardly describing an arc of a circle having as its center the pivotal connection between the upper ends of said arms and toggle links 51 and 52. Rocker arms 39 and 40 being connected to brake 115 drag- rods 30 and 31 the inward movement of said arms simultaneously retracts the rods and applies the brake bands which they control.

On the other hand, should either of the 120 speed shifting levers, for instance lever 45, be in an active or power applying position, pressure upon the foot pedal 41, will not effect the brake assembly in that control unit having its shifting lever thus positioned, for 125 the reason, shifting lever 45 from neutral to a power applying position disrupts the toggle connection between arm 50 and the upper end of rocker arm 40, causing the lower end of said rocker arm (to which 130

drag-rod 31 is affixed) to move inwardly describing an arc of a circle having as its center the pivotal connection between rocker arms 40 and the cross head of hanger 5 38, (as shown in dotted outlines Fig. 4). When the rocker arm is in this position, the throw of foot lever 41, is insufficient to remove said slack and at the same time apply the brakes.

10 This situation, however, does not obtain with respect to brake drag-rod 30 and rocker arm 39 to which it is connected, inasmuch as the toggle connection between the upper end of rocker arm 39, and rocker arm 49 15 is unbroken. Pressure upon the foot brake will therefore cause arm 49 to move from the point of its pivotal connection with links 51 thus applying the brake controlled by drag-rod 30. In other words effectual operation of the brakes depends entirely upon the condition of the toggle connection between toggle arms 49 and 50 and rocker arms 39 and 40, if this toggle is unbroken, the braking assemblies are effective while, 20 if it is broken, application of the brake becomes impossible.

When the shifting lever of either unit is in inactive or neutral position, the track controlled by this lever is idle, therefore, 30 if the braking assemblies are effective only in the unit having its lever in neutral position, it follows operation of the foot lever does not apply the brakes other than the idle track.

35 The operation of the clutch and reverse assemblies are self evident and requires no explanation other than to say that movements of these levers actuate the hangers to which they are connected and in turn 40 actuate the clutch and reverse drag-rods thus operating the clutch and reverse mechanism.

To reverse the mechanism put both shifting levers in neutral, put clutch in neutral, 45 and when the mechanism has stopped rotating forward put the reverse lever in reverse position.

In conclusion, it becomes evident, this invention accomplishes several very important 50 operations in tractor control to wit: complete release of the low speed bands at the time of applying the high speed mechanism, a differentiating brake control, by means of which the brakes apply only to the idle 55 track; and a speed changing arrangement, requiring restoration of speed control to its initial inactive position as a prerequisite to changing from one speed to another.

Having described the invention, what I 60 claim as new is:—

1. A control mechanism for a tracklaying tractor, comprising two separate speed changing controlling units, each unit operated by a shifting lever, a track brake 65 control connected to both of said levers, and

a single foot pedal for operating said track brake control, said connection displaced by the shifting of the lever from neutral to prevent application of braking pressure on the mechanism controlled by such lever.

2. A control mechanism for a tracklaying tractor, comprising a control unit for each track, each unit comprising a high and low speed selector and a shifting lever for operating said selectors, and a differentiating 70 track brake mechanism connected to each shifting lever, the connection displaced by the shifting of a lever from neutral to prevent application of braking pressure to the mechanism controlled by such lever.

3. A control mechanism for a tracklaying tractor, comprising two control units one for each track, each unit comprising a high and low speed selector, a lever for operating said selectors, a track brake in each unit operated by a single lever, and connections 85 between the said levers and the brake lever displaced by the throw of said first mentioned levers from neutral to prevent application of braking pressure.

4. A control mechanism for a tracklaying tractor, comprising two independent units, each unit embodying a high and low speed selector connected to high and low speed brakes, a shifting lever for operating said 95 selectors, a track brake cooperating with said shifting lever, a brake lever for applying a braking pressure to both of said tracks and connections between the brake lever and the shifting levers displaced when the shifting levers are moved from neutral to prevent application of braking pressure.

5. A control mechanism for a tracklaying tractor, comprising a separate unit for each track, each of said units embodying high 105 and low speed selectors, a shifting lever operating said selectors, a track brake control, a single lever connected to the brake control of both units, and connecting means between the track brake control and shifting lever 110 of each unit, displaced by the movement of the shifting lever from neutral to prevent the application of braking pressure to the unit controlled by such lever.

6. A control mechanism for a tracklaying 115 tractor, comprising a control unit for each of said tracks, each unit comprising high and low speed selectors, and a shifting lever operating said selectors; a track brake control assembly in each unit, a single lever 120 governing the operation of both assemblies, a toggle connection between the braking assembly and the shifting lever of each unit so that a movement of the shifting lever breaks the toggle and renders the braking 125 assembly to which it is connected ineffective.

7. A control mechanism for tracklaying tractors, comprising two units, one for each track, a clutch and reverse mechanism common to both units, each unit embodying high 130

- and low speed selectors, a shifting lever operating said selectors, a track brake assembly for each unit, a single operating lever for said assemblies, connections between said shifting levers and said assemblies to render the latter inoperative upon actuation of the former, and co-acting means between the high and low speed to impart slack to the low speed at the time of applying the high speed control. 10
8. A control mechanism for tracklaying tractors, comprising two separate units, a common clutch lever, high and low speed selectors and a shifting lever for each unit, a reverse control, a breaking control, co-acting means between the shifting lever and brake control of each assembly serving to render said brake control inoperative when its cooperating shifting lever is in power applying position, and co-acting means between the high and low speed selectors to impart slack to the latter when the high speed selector is moved to active position. 15
9. A control mechanism for tracklaying tractors, comprising a transversely extending shaft, a brake lever mounted on said shaft, a shifting lever positioned on each side of said brake lever, said shifting lever having rearwardly extending toggle arms, toggle links pivotally fastened to the outer ends of said arms and normally maintained in alinement therewith, a supporting hanger, a pair of rocker arms carried by said hanger, the upper extremities of said rocker arms being pivotally fastened to said toggle links; control rods connected to the lower end of said arms, a yoke fastened to said brake lever and connected to the central portion of said rocker arms, said yoke serving to retract said rocker arms and control rods connected therewith, providing the toggle connections between the shifting levers and rocker arms have not been broken. 20
10. A control mechanism for tracklaying tractors, embodying two units, each unit comprising a high and low speed selector, a brake control, and shifting lever for engaging the high and low speed selectors, said shifting lever being connected to the braking control, said high speed selectors being provided with rearwardly and downwardly extending arms; a hanger, a rod connection between the downwardly extending arm of said high speed selector and said hanger, a high speed control drag rod connected to the free end of said hanger, a rocker arm, a toggle connection between the rocker arm and the rearwardly extending arm of said high speed selector, a low speed control rod 60 secured to the lower end of said rocker arm whereby operation of the low speed selector retracts the low speed control rod, and actuation of the high speed selector operates the high speed control rods and simultaneously 65 disrupts the toggle connection between the high speed selector and the low speed rocker arm to impart slack to the low speed control rod. 70
11. A control mechanism for tracklaying tractors, embodying two units, each unit having a breaking and speed assembly, the speed assembly having active and inactive positions, a common operating member for the two braking assemblies, and co-acting means 75 between the speed and braking assemblies of each unit, the speed assembly when in active position serving to render the braking assembly with which it co-operates inactive during the actuation of said common member. 80
12. A control mechanism for tracklaying tractors, embodying two units, each unit having a breaking, a high and a low speed assembly, a common controlling member for 85 both braking assemblies, a shifting lever in each unit to selectively engage the high and low speed assemblies, said lever having active and inactive positions; and co-acting means between the shifting lever and braking assembly of each unit serving to render such braking assembly inoperative when the shifting lever is in active position. 90
13. A control mechanism for tracklaying tractors, embodying two units, each unit having a high and a low speed assembly, a shifting lever to selectively operate said assemblies, said lever having active and inactive positions, a toggle connection between the high and low speed assemblies, said toggle 95 connection functioning to release the low speed assembly when the high speed assembly is brought to active position. 100
14. A control mechanism for tracklaying tractors, comprising two units, each unit having a brake assembly and a high and a low speed assembly, said high and low speed assemblies having active and inactive positions, means for applying the braking assembly to either track, means for shifting the high speed assembly to active position and simultaneously releasing the low speed assembly, said last mentioned means restoring the low speed assembly to initial position when the high speed assembly is returned to its inactive position. 105 110 115

LAWRENCE R. BUCKENDALE.
